SHOCKPROOF X-RAY TILT TABLE

Albert C. Nelson, Flushing, N. Y., assignor to
Westinghouse X-Ray Company, Inc., a corpora-
tion of Delaware

Application September 29, 1934, Serial No. 746,037

7 Claims. (Cl. 250—34)

My invention relates to X-ray apparatus and has particular relation to X-ray tilt tables employed by the roentgenologists for the making of radiographic and fluoroscopic examinations wherein the entire device is rendered shockproof to prevent accidental shocks resulting to a patient or an operator.

In the prior art X-ray tables of this type are well known for enabling a patient, when lying upon the table to be moved to various angular positions from below a horizontal or what is known as the Trendelenberg position, to a vertical position. It is customary to provide such tables with facilities for the taking of both radiographic and fluoroscopic examinations, which in the first instance, usually comprises a tube column movable longitudinally of the table upon guide rails so that the X-ray tube carried thereby may be properly aligned with any desired portion of a patient's anatomy and a radiographic carriage holding a sensitized film.

The fluoroscopic apparatus normally employed consists of an X-ray tube and adjustable fluoroscopic shutters supported by a longitudinally and transversely movable carriage below the table top and a fluorescent screen above the table top. The high potential electrical energy for energizing the fluoroscopic X-ray tube has, heretofore, been supplied through a mast unit comprising high tension insulators extending from a housing disposed at one end of the table and connected to overhead conductors leading to the high voltage source, as shown in my prior Patents Nos. 1,874,582 and 1,957,720.

This housing in turn is supplied with cord reels connected to the high tension conductors extending through the insulators and to the terminals of the fluoroscopic X-ray tube thus enabling the connections for the tube to be lengthened or shortened depending upon the direction of movement of the table top to its various angular positions. In order to prevent accidental contact with the high tension conductors by an operator or patient a wire guard or screen is usually provided between the high tension housing and the table supporting standards.

In such construction, while the high tension conductors are more or less shielded when the table is in the horizontal or Trendelenberg position, as the same approaches the vertical the high tension conductors, as well as the X-ray tube, move in such a manner as to be no longer disposed between the shield or guard. This accordingly exposes the high tension parts and increases the hazard of shocks resulting to a patient or

operator who might accidentally contact the same. Moreover, the necessity for the provision of a housing at one end of the table prevents access all around the table rendering it inconvenient to properly position a patient thereupon.

It is accordingly an object of my present invention to provide an X-ray tilt table which is of entirely shockproof construction.

Another object of my invention is the provision of an X-ray tilt table wherein all high tension carrying parts are completely enclosed in all positions of the table.

Another object of my invention is the provision of a shockproof X-ray tilt table in which the fluoroscopic X-ray tube, disposed below the table top, is totally enclosed and is energized by grounded metallic sheathed cables thus rendering the device shockproof.

A further object of my invention is the provision of an X-ray tilt table wherein the fluoroscopic X-ray tube is energized through metallic sheathed high tension cables in any position of the table without undue flexing thereof tending to cause a disruption of the cables, and the necessity for a high tension housing is eliminated thus permitting ready access to both ends of the table to facilitate the proper positioning of a patient.

Still further objects of my present invention will become obvious to those skilled in the art by reference to the accompanying drawings wherein:

Figure 1 is a perspective view of a shockproof X-ray tilt table constructed in accordance with my present invention.

Fig. 2 is a side elevational view partly in section and with parts of the table broken away to better illustrate the device, and

Fig. 3 is an end view in elevation of the table shown in Fig. 1 with some of the parts broken away.

Referring now to the drawings in detail I have shown in Fig. 1, a base member comprising a pair of uprights or standards 5 and 6, which may be formed of welded sheet metal parts as shown and claimed in my copending application, Serial No. 704,633; filed December 30, 1933, and cross braces 45 7 and 8 may interconnect these standards to increase the rigidity of construction. These standards, near their upper ends, are provided with a short extension 9 housing suitable bearings, such as ball races (not shown), to which a 50 table top, shown generally at 12, for supporting the body of a patient, is pivotally journaled by the engagement of short shafts 13 and 14 with the bearings provided in the standards 5 and 6. The transverse axis formed by the shafts 13 and 55

14 is so disposed relative to the entire table and the standards that the weight is substantially equalized for the purpose of increasing the ease with which the table can be rotated.

- 5 The table top 12 comprises a panel of X-ray pervious material, such as wood veneer or a phenolic condensation product, supporting same upon a rectangular frame 15, to which the shafts 13 and 14 are connected. The panel is secured to the 10 frame by means of an angular stainless steel retaining strip 16 flush with the table top surface, to enhance the appearance of the table as well as the ease of placing and removing a patient therefrom. This rectangular frame 15 may be constructed of the same material as the uprights 5 and 6, and is provided with a spacing immediately below the panelled top to enable a radiographic carriage 17, which carries the usual cassette tray for housing the sensitized films and 15 the Bucky grid (not shown), to be moved to any desired position longitudinally of the table. A housing, shown generally at 18, is suitably secured, such as by welding or the like, to the rectangular frame 15. The side walls thereof have 20 a portion of substantially semispherical configuration which are suitably reinforced and have secured thereto a curved rack bar or sprocket chainring 19 thus forming segmental gears for moving the table to its various angular positions.
- 25 30 For the purpose of rotating the table top about its axis formed by the pivots 13 and 14, mechanism (not shown) is carried by the base member provided with suitable gearing engageable with the segmental gears 19 which may be operated either manually by rotation of a hand crank 20 or by an electric motor as more specifically shown and described in my aforementioned copending application. As the details of construction of this mechanism per se, nor its 35 40 particular mode of operation, forms no part of my present invention further detailed description thereof is deemed unnecessary.

When it is desired to utilize the X-ray table for a radiographic examination an X-ray tube 22, which is carried by a tube column 23 movable longitudinally of the table upon suitable guide rails 24, is moved into position to align with the desired portion of a patient's anatomy and the sensitized film carried by the radiographic carriage, in the 50 usual manner as is well known in the art, and shown in my prior Patent No. 1,957,720, issued May 8, 1934.

A fluoroscopic carriage 25 is also adapted to move transversely and longitudinally of the table 55 top and supports a fluorescent screen 26 above, and a suitably ray shielded X-ray tube 27 and adjustable fluoroscopic shutters below the table top. In order to conduct high potential electrical energy to the fluoroscopic X-ray tube 27 a pair of grounded metallic sheathed high tension cables 28 and 29 is connected to a high potential source, such as a high tension transformer (not shown). These cables may be connected directly to such transformer and laid across the floor or 60 to an overhead system as shown in Fig. 1 which in turn is connected to the high tension source.

The remaining ends of the high tension cables 28 and 29 are secured to suitable insulators 30 and 32 carried by a pair of uprights 33 supported by a brace member 34 extending between the standards 5 and 6 and forming part of the base member. The conductors of the respective cables are in turn electrically connected to self feeding and retractable wire reels 35 and 36 carried by 65 the insulators with the reel conductors connected

to the terminals of the X-ray tube 27. The housing 18 is provided with slots 37 and 38 on the underside thereof for the purpose of enabling the table top to be rotated about its pivot without interfering in any way with the cables 28 and 5 29 or insulators 30 and 32 which extend well into the housing 18 thus obviating accidental contact with all high tension carrying parts by an operator or patient.

In order to permit access to the fluoroscopic 10 tube or other parts the housing 18 is provided with a door 39 hinged at 40 and normally fastened by means of thumb screws 42.

It thus becomes obvious to those skilled in the art that I have provided a completely shock- 15 proof X-ray examination table in which all high tension carrying parts are totally enclosed. The X-ray tube disposed below the table top for the making of fluoroscopic examination is supplied with high tension electrical energy through 20 grounded metallic sheathed cables which are connected to the tube interiorly of the housing and extend thereinto in such a manner as to preclude the possibility of shocks resulting to a patient or operator. Moreover, the table may be moved 25 to any desired angular position without in any way disturbing the high tension metallic cables, thus preventing undue flexing thereof tending to cause wear or disruption, and the entire table remains shockproof in all its various positions. 30 Inasmuch as the high tension cables extend into the table housing the necessity for a fluoroscopic high tension mast and housing at one end of the table is eliminated which renders both ends of the table accessible to an operator thus increasing 35 the facility of properly positioning patients upon the table.

Although I have shown and described one specific embodiment of my present invention I do not desire to be limited thereto as various other modifications thereof may be made without departing from the spirit and scope of the appended claims. 40

What is claimed:

1. In a shockproof X-ray examination table, the combination of a pair of standards, a table 45 top pivotally supported upon said standards and rotatable to various angular positions, a fluoroscopic carriage movable longitudinally of said table top provided with an X-ray tube disposed below and a fluorescent screen above said table top, a remotely disposed source of high potential electrical energy for energizing said X-ray tube, means secured to the underside of said table top and totally enclosing the portion of said fluoroscopic carriage below said table top together with 50 said X-ray tube and all exposed high tension carrying parts to prevent accidental shocks resulting to a patient or operator when said table is moved to any of its various angular positions and insulated means extending through said 55 last mentioned means and connecting said X-ray tube to said remotely disposed source for transmitting electrical energy therebetween and to prevent accidental shocks resulting to a patient or operator upon contacting the same. 60

2. In a shockproof X-ray examination table, the combination of a pair of standards, a table top supported upon said standards and rotatable to various angular positions, a fluoroscopic carriage movable longitudinally of said table top 70 provided with an X-ray tube disposed therebelow and adapted to be energized by high potential electrical energy from a suitable source, a housing secured to the underside of said table top and totally enclosing said X-ray tube and all ex- 75

posed high tension carrying parts to prevent accidental shocks resulting to a patient or operator, and grounded metallic sheathed cables extending into said housing for supplying high tension electrical energy from said source to said X-ray tube in all angular positions of said table.

3. In a shockproof X-ray examination table, the combination of a pair of standards, a table top pivotally supported upon said standards and rotatable to various angular positions, a fluoroscopic carriage movable longitudinally of said table top provided with an X-ray tube disposed therebelow and adapted to be energized by high potential electrical energy from a suitable source, a housing secured to the underside of said table top and forming a closure for said X-ray tube and all exposed high tension carrying parts to prevent accidental contact therewith by a patient or operator, means secured to said housing for causing movement thereof with attendant movement of said table top about its pivot to various angular positions, and grounded metallic sheathed cables extending into said housing for supplying high tension electrical energy from said source to said X-ray tube in all angular positions of said table without interfering with the movement of said housing and table top.

4. In a shockproof X-ray examination table, the combination of a base member including a pair of standards, a table top pivotally supported upon said standards and rotatable to various angular positions, a fluoroscopic carriage movable longitudinally of said table top provided with an X-ray tube disposed therebelow and adapted to be energized by high potential electrical energy from a suitable source, a housing secured to the underside of said table top and forming a closure for said X-ray tube and all exposed high tension carrying parts to prevent accidental contact therewith by a patient or operator, high tension insulators rigidly supported by said base member and extending into said housing and provided with self-feeding and retractable means connecting said insulators to said X-ray tube in all angular positions of said table top, and grounded metallic sheathed cables connected to said insulators for supplying high potential electrical energy from said source to said last mentioned means and to said X-ray tube.

5. In a shockproof X-ray examination table, the combination of a base member including a pair of standards, a table top pivotally supported upon said standards and rotatable to various angular positions, a fluoroscopic carriage movable longitudinally of said table top provided with an X-ray tube disposed therebelow and adapted to be energized by high potential electrical energy from a suitable source, a housing provided with a pair of longitudinally extending slots secured to the underside of said table top and movable therewith, said housing forming a closure for said X-ray tube and all exposed high tension carrying parts to prevent accidental contact therewith by an operator or patient, a pair of high tension

insulators rigidly supported by said base member and extending through said slots into said housing to enable movement of the latter and rotation of said table top to various angular positions about its pivot and provided with conductive members connected to said X-ray tube, and grounded metallic sheathed cables connected to said insulators for supplying electrical energy from said source through said insulators and said members to said X-ray tube in all angular positions of said table top.

6. In a shockproof X-ray examination table, the combination of a base member including a pair of standards, a table top pivotally supported upon said standards and rotatable to various angular positions, a fluoroscopic carriage movable longitudinally of said table top provided with an X-ray tube disposed therebelow and adapted to be energized by high potential electrical energy from a suitable source, a housing provided with a pair of longitudinally extending slots secured to the underside of said table top and forming a closure for said X-ray tube and all exposed high tension carrying parts to prevent accidental contact therewith by a patient or operator, a pair of high tension insulators rigidly supported by said base member and extending through said slots into said housing to enable movement of the latter and rotation of said table top to various angular positions about its pivot, yieldable means carried by said insulators and connected to said X-ray tube in all angular positions of said table top, and grounded metallic sheathed cables connected to said insulators for supplying electrical energy from said source to said yieldable means and to said X-ray tube.

7. In a shockproof X-ray examination table, the combination of a base member including a pair of standards, a table top pivotally supported upon said standards and rotatable to various angular positions, a fluoroscopic carriage movable longitudinally of said table top provided with an X-ray tube disposed therebelow and adapted to be energized by high potential electrical energy from a suitable source, a housing provided with a pair of longitudinally extending slots secured to the underside of said table top and forming a closure for said X-ray tube and all exposed high tension carrying parts to prevent accidental contact therewith by a patient or operator, means secured to said housing for causing movement thereof with attendant movement of said table top about its pivot to various angular positions, a pair of high tension insulators rigidly supported by said base member and extending through said slots into said housing to enable movement of the latter and said table top, yieldable means carried by said insulators and connected to said X-ray tube in all angular positions of said table top, and grounded metallic sheathed cables connected to said insulators for supplying electrical energy from said source to said yieldable means and X-ray tube.

ALBERT C. NELSON.
